E. GERMER, JR.
BURNER.
FILED JAN. 4, 1922.

UNITED STATES PATENT OFFICE.

EDWARD GERMER, JR., OF ERIE, PENNSYLVANIA.

BURNER.

Application filed January 4, 1922. Serial No. 526,883.

To all whom it may concern:

Be it known that I, EDWARD GERMER, JR., a citizen of the United States, residing at Erie, in the county of Erie and State of Pennsylvania, have invented new and useful 5 Improvements in Burners, of which the following is a specification.

With stoves having hollow radiants into which the flame is injected difficulty has 10 been experienced with burners having burner caps with slotted openings therein in providing a flame that would reach the upper end of the radiants. According to the present invention the cap is so constructed as to assure an upward direction to the flame so as 15 to reach the upper ends of the radiant.

The invention is illustrated in the accompanying drawings as follows:—

Fig. 1 shows a front elevation of a stove, 20 the burner being in section to better show construction.

Fig. 2 a plan view of one of the burner caps.

Fig. 3 a central section through one of the 25 burner caps.

1 marks the stove base, 2 the stove frame, 3 the burner chamber, 4 the inlet pipe leading to the burner chamber, 5 the mixer, and 6 the gas supply jet.

Caps 8 are arranged in a series along the 30 top of the burner chamber 7 and the radiants 9 are arranged over these caps, the burner having the shoulders 9^a on which the radiants rest.

The caps have the side walls 10 and top 35 walls 11 and these have the slits 12 which extend through them, the slits being lengthwise of the burner so that they may be all molded at one operation, thus making a very satisfactory jet opening for the flame.

By making the walls 10 of greater thickness than the walls 11 a greater resistance

to the flow of gases toward the sides is interposed than through the top of the cap. As a consequence the flame is projected upwardly so as to reach the upper ends of the radiants. 45

What I claim as new is:—

1. In a burner, the combination of a burner chamber; an upwardly extending cap 50 communicating with the chamber; and slits extending through the top wall of the cap below the lower surface of said top wall and into the side walls of the cap, the side walls of the cap being thicker than the top wall 55 to confine the flame from the jets.

2. In a burner, the combination of a burner chamber; an upwardly extending cap communicating with the chamber; slits extending through the top wall of the cap below the lower surface of said top wall and into the side walls of the cap, the side walls of the cap being thicker than the top wall 60 to confine the flame from the jets; and an elongated hollow radiant arranged over the 65 cap.

3. In a burner, the combination of a burner chamber; an upwardly extending cap; slits extending through the walls of the cap, the walls of the cap being arranged to confine the flame issuing from the slits; and an elongated hollow radiant arranged over the 70 cap.

4. In a burner, the combination of a burner chamber; an upwardly extending cap 75 communicating with the chamber; and slits extending through the top wall of the cap below the lower surface of the top wall and into the side walls of the cap, said top and side walls differing in thickness to control 80 the form of the flame from the slits.

In testimony whereof I have hereunto set my hand.

EDWARD GERMER, Jr.
